UNITED STATES PATENT OFFICE

1,937,450

SAGGER AND METHOD OF MAKING THE SAME

August Weber, Jr., Schenectady, N. Y., assignor to Weber Electric Company, Schenectady, N. Y., a corporation of New York

Application July 6, 1932. Serial No. 621,111

6 Claims. (Cl. 25—153)

The present invention relates to an improved sagger and method of making the same.

In the firing of porcelain and other earthenware articles, it is the practice to subject these articles to extremely high temperatures in a kiln or furnace. As the clay or other material, of which the porcelain articles are made, is introduced into the kiln in a green state it is very delicate and fragile. Consequently, it has been found necessary to protect the articles during the firing operation from the direct action of the heating gases in the kiln by positioning them in saggers that may be conveniently mounted or stacked one upon the other within the kiln. As will be appreciated, it is extremely desirable that the capacity of the kiln be such as to accommodate as large a number of saggers as possible and that the heating operation be effected expeditiously and economically.

20 A primary object of the present invention is to provide means for increasing the exposed heating surface of the saggers and to reduce the weight thereof so as to effect a substantial saving in fuel consumption during the firing operation.

25 A further object consists in a new and improved method of forming corrugated saggers having a concave or arch-shaped bottom in order to provide a relatively light sagger without impairing or lessening its strength and efficiency.

30 A further object of the invention is to provide a sagger with means for facilitating the heating and cooling of the articles carried by the saggers at a minimum expenditure of time and labor.

Other objects and advantages of the invention will become apparent from the following description when taken in conjunction with the accompanying claims and drawings.

Referring to the drawings, in which is shown a preferred embodiment of the invention,

40 Figure 1 is a sectional view taken substantially along the line 1—1 of Figure 2, showing a sagger having my invention applied thereto.

Figure 2 is a sectional view taken substantially along the line 2—2 of Figure 1.

45 Figure 3 is a sectional view of a molding apparatus for forming the sagger.

Figure 4 is a sectional view taken substantially along the line 4—4 of Figure 3.

50 Referring to the drawings in which like numerals indicate like parts in the several views, and more particularly, Figures 1 and 2, 10 designates a sagger formed in accordance with my invention, and has its exposed cylindrical side wall 11 provided with means for increasing the heating surface of the sagger, which means pref-

erably consist of a series of circumferentially disposed corrugations or grooves 12 that extend from a point beneath the top of the sagger to a point short of the opposite end thereof. Obviously, the increased heating surface may be disposed in a different position than that shown and may assume various other shapes. The outer wall of the bottom 13 is preferably formed with a concave or arched shape surface 14, while the inner surface 15 is preferably horizontally disposed so as to extend substantially parallel with the plane of the upper end or edge of the sagger. The corrugations 12, it will be seen not only increase the exposed heating surface, but also substantially reduce the weight of the sagger, while the concave bottom 14 acts to further reduce the weight of the sagger, and also permits the saggers to be stacked or placed one upon the other in the furnace, so that the articles carried thereby may extend a limited distance within the adjacent sagger without being distorted or engaging therewith.

55 The sagger is preferably shaped in a molding apparatus that has a hollow supporting member 16 which receives the outer die or shell 17 and the inner die or plunger 18 (Fig. 3). The member 16 has its bottom closed by a reciprocating piston 19 that is actuated by a shaft 20 which is connected to any suitable driving mechanism such as that shown in my Patent No. 676,806, Jan. 18, 1901.

60 The die 17 is preferably formed with sectional side walls 20 that are hinged together as at 21 (Fig. 4), so that when the die is removed from the member 16, after completion of the molding operation of the sagger 10, the sections 20 may swing about their hinges 21, so as to be conveniently withdrawn from the outer wall of the corrugated sagger. While any number of sections 20 may be employed, six are preferably used. The inner wall of each of the sections 20 may be provided with curved projections or ribs 22 for forming the corrugations 12 in the outer or exposed wall of the sagger 10. The die 17 has its bottom 23 supported by the piston 19 when it is inserted in the molding apparatus and has its upper surface provided with a substantially convex shaped portion 24 for forming the concave wall 14 of the sagger. The inner die or plunger 18 is provided with an upper peripheral annular flange 25, which snugly engages the adjacent wall of the die 17 to prevent the escape of the clay during the molding operation. In order to form the concave surface 14 in the bottom 13 of the sagger and insure the bottom maintaining the de-

sired shape during the firing and drying operation, a steel disc 26 is preferably positioned within the die 17 and is of substantially the same configuration as the convex upper surface 24.

5 To form the sagger 10 it will be assumed that the piston 19 and outer die 17 are in the position as shown in Figure 3, while the inner die 18 is withdrawn from the member 16 a sufficient distance to permit access to the die 17. The desired 10 amount of green clay to form the sagger is first placed on the disc 26 and the die 18 is then introduced into the outer die 17 until the inner die engages the plastic mass of clay. Further downward movement of the inner die 18 causes the 15 plastic material to be compressed between the convex bottom 24 and the corrugated walls of the sections 20. During this operation the material is forced to flow upwardly around the inner die until it engages the flange 25, so as to 20 completely fill the mold cavity. After the molding operation has been completed the outer die member 17 and its associated parts are withdrawn from the member 16 by the upward movement of the piston 19. The whole mass is raised 25 until the bottom edge of the sectional die 17 is flush with the top of the shell or member 16. The die 17 is then removed so that the sagger is attached to and supported by the plunger 18 and the bottom plate 23. The plate 23 is then removed 30 from the sagger by inserting a suitable tool such as a bradawl between the disc 26 and the bottom so as to separate these parts. The plate 23 may then assume its position in engagement with the piston 19. The shaft 27 is then 35 raised so that a sagger board or pallet (not shown) may be placed upon the top of the shell 16, so as to support the core or inner die 18 with the green sagger and attached disc 26. The inner die 18 is then removed from the sagger by the 40 bradawl tool by piercing a hole through the clay wall of the sagger along the line of the bottom of the die which permits the air to enter so that the die may readily be removed. This completes the 45 operation leaving the pressed or formed sagger on the board with the disc 26 still attached to the bottom of the green sagger. After the formed sagger has sufficiently dried, the metallic disc 26 is withdrawn from the bottom, so that the sagger assumes the final shape as shown in 50 Figure 1.

It will be seen that by reason of the present invention the exposed heating surface of the sagger is substantially increased and the weight reduced without impairing the strength or efficiency of the sagger. In other words, the total surface of the sagger exposed to heat is about thirty per cent greater than that of the old style un-corrugated sagger, so that while my sagger is of substantially the same size and capacity as the standard types, it is more quickly heated and cooled, and effects a saving of about one-third in total weight over the type of saggers now in use. As my sagger is about seven pounds lighter

65 than those as heretofore made, it will be seen that in a kiln having a capacity of two thousand saggers, the use of my invention effects a total saving in weight of about fourteen thousand pounds and a corresponding saving in fuel consumption.

70 Saggers employed in treating electrical porcelain articles are rather heavy, so that the bottom saggers are subjected to a considerable load. As the concentric stacks of articles to be treated are piled up from around the center towards the outer edge of each sagger, it will be evident that the load is gradually increased to the thicker part of the bottom 13. It has been found in actual practice that even after the sagger constructed in accordance with my invention has been used from ten to fifteen times, the bottom does not sag or fall below the level of the old style saggers having parallel bottoms. Consequently, my improved sagger can always be placed 75 on top of another sagger that is completely filled or loaded and no allowance has to be made for bottoms that have dropped or sagged.

Saggers employed in treating electrical porcelain articles are rather heavy, so that the bottom saggers are subjected to a considerable load. As the concentric stacks of articles to be treated are piled up from around the center towards the outer edge of each sagger, it will be evident that the load is gradually increased to the thicker part of the bottom 13. It has been found in actual practice that even after the sagger constructed in accordance with my invention has been used from ten to fifteen times, the bottom does not sag or fall below the level of the old style saggers having parallel bottoms. Consequently, my improved sagger can always be placed on top of another sagger that is completely filled or loaded and no allowance has to be made for bottoms that have dropped or sagged.

It is to be understood that the sagger and method of forming the same is merely illustrative of a preferred embodiment and that such changes may be made without departing from the spirit of the invention as fall within the purview of one skilled in the art and the scope of the appended claims.

I claim:

1. A sagger having its exposed wall formed with corrugations for increasing the heating surface of the sagger and reducing the weight thereof.
2. A sagger having its bottom provided with a horizontally disposed upper surface and a concave undersurface, the outer side wall of the sagger provided with spaced corrugations for increasing the heating surface of the sagger and reducing the weight thereof.
3. A sagger having its bottom provided with an exposed concave surface and the side wall thereof formed externally with corrugations for increasing the heating surface of the sagger and reducing the weight thereof.
4. A sagger having its side wall formed with means for increasing the heating surface thereof, said means being positioned wholly within the plane of the wall of the sagger.
5. A sagger having its exposed wall formed with means for increasing the heating surface and reducing the weight of the sagger, said means being positioned wholly within the plane of the outer wall of the sagger.
6. The method of making saggers which consists in forming spaced corrugations in the outer wall of the sagger and forming the bottom with a concave surface and temporarily attaching a shape holder to the bottom whereby to insure the latter retaining its shape until the sagger has hardened.

AUGUST WEBER, JR.
